Primary Examiner — Jennifer Rivard*Assistant Examiner* — Catherine S Posthauer(74) *Attorney, Agent, or Firm* — McCracken & Gillen LLC(57) **CLAIM**

The ornamental design for a sound absorbing panel assembly, as shown and described.

DESCRIPTION

FIG. 1 is a side perspective view of a first embodiment of a sound absorbing panel assembly, showing my new design; FIG. 2 is an isometric view of the first embodiment; FIG. 3 is a front perspective view of the first embodiment; FIG. 4 is a front elevation view of the first embodiment; FIG. 5 is a side perspective view of a second embodiment of the sound absorbing panel assembly;

FIG. 6 is an isometric view of the second embodiment; FIG. 7 is a front perspective view of the second embodiment; and,

FIG. 8 is a front elevation view of the second embodiment. The broken lines shown in FIG. 6 depict subject matter which forms no part of the second embodiment of the claimed design.

1 Claim, 8 Drawing Sheets(56)
